PATENTED DEC. 19, 1905.

A. L. BURT.

APPARATUS FOR MAKING GAME BALLS.

APPLICATION FILED DEG. 5, 1901.

UNITED STATES PATENT OFFICE.

ALONZO L. BURT, OF MILBURN, NEW JERSEY.

APPARATUS FOR MAKING GAME-BALLS.

No. 807,436.

Specification of Letters Patent.

Patented Dec. 19, 1905.

Application filed December 5, 1901. Serial No. 84,750.

To all whom it may concern:

Be it known that I, ALONZO L. BURT, a citizen of the United States, and a resident of Milburn, Essex county, State of New Jersey, have 5 invented certain new and useful Improvements in Apparatus for Making Game-Balls, of which the following is a specification.

My invention relates to apparatus for making game-balls, such as pool-balls, and has for 10 its object to provide means whereby the balls may be obtained quickly and made of a homogeneous character—that is, each part of the ball will undergo substantially the same treatment.

15 The invention will be fully described hereinafter and the features of novelty pointed out in the appended claims.

Reference is to be had to the accompanying drawings, in which—

20 Figure 1 is an elevation, partly in section, of a mold constructed according to my invention. Fig. 2 is a side elevation of an apparatus in connection with which my improved mold may be used; and Fig. 3 shows the same 25 apparatus and mold with dies of a different shape, as will be fully explained hereinafter.

My improved mold consists of a cylindrical hollow body A, open at both ends and provided, preferably at its center, with transverse 30 apertures located at diametrically opposite points and extending from the bore A' of the body to the outside thereof. These apertures, as shown, are screw-threaded and are adapted to receive plugs having smooth cylindrical 35 ends B, adapted to project into the bore of the mold-body, screw-threaded portions B', and outer heads B'', by means of which the plugs may be moved in or out. It will be understood that the plugs are thus movable, so 40 that they may be projected into the bore A' or withdrawn therefrom. This mold is adapted for use in conjunction with a press or set of dies of any suitable construction, and it will be understood that the construction shown 45 in Figs. 2 and 3 is only an example of such press and does not in its details form any part of my present invention. As illustrated in said figures, the mold-body A is stationary and is connected with arms C, in which is 50 formed a bearing C' for a screw-spindle D, provided with an operating-wheel D'. The screw-spindle D has two screw-threads of opposite pitch, and the thread which engages the bearing C' has only one-half the pitch of the 55 other thread, which is shown below said bearing. The thread of greater pitch engages a

bearing or nut E² upon a frame E, which is guided along the arms C, so that it can slide thereon, but cannot turn. The frame E has a cross-bar E', on which the lower die is adapted to be supported, while the spindle D presses against the upper die. It will be understood that by screwing the spindle D inward the upper die and the lower die will be forced toward each other, each having a movement of 65 the same extent.

In operation the apparatus is used as follows: The lower die F is first inserted alone, and the cavity or bore A' of the mold is filled with loose material G. It will be understood 70 that the die F is first in its lowermost position with its stop flush with the bottom of the mold. The loose material employed by me is plastic material of any suitable composition. The dies F F', which I employ in the first 75 stage of my manufacture, have cup-shaped or spherically-curved recesses on their inner surfaces surrounded by annular plane surfaces. After the mold has been filled, as described, the ends B of the plugs being within the mold, 80 as shown in Fig. 2, the upper die F' is placed on top of the loose material and the hand-wheel D' is turned so as to force the dies evenly toward each other. The result will be a firmly-compressed body or core of plastic 85 material, such as indicated by the letter G' in Fig. 3, which core consists of a cylindrical portion with spherically-curved knobs or caps projecting therefrom at the ends. This body is held in its central position by the ends B of 90 the plugs, so that it will not drop when the dies F F' are moved outwardly. This operation being completed, the dies F F' are withdrawn and a lower die H of a somewhat different form is placed on the cross-bar E' in 95 such a manner that the upper end of said die will be flush with the lower end of the mold. A suitable amount of loose material G² is inserted between the core G' and the lower die H and a like quantity of loose material G³ is 100 put on top of the core G'. The dies H H' are cylindrical, with spherical recesses in their ends, said recesses being of much larger diameter than those of the dies F F' and extending almost to the outer edges of the dies. When 105 the dies H H' are moved toward each other, the loose material G² G³ will be pressed into a solid body, which will be united with the core G' sufficiently to enable the ball roughly formed in this manner to be further handled 110 in the usual way. After the dies H H' have been removed from the mold the compressed

- ball, consisting of the core G' and two spherically-curved end pieces, will be withdrawn from the mold by simply screwing the plugs outward until they release the core G' and then pushing the ball out of the mold endwise. These compressing processes are carried out while the material is in a cold state, and therefore without destroying the valuable property of the material to become more firmly united by the application of heat. The end portions B of the plugs serve not only to hold the core G' in its central position, but principally to form recesses in said core which will be adapted to receive the spots which are used in game-balls of this character. These spots are formed in the usual manner by compression from material of the same nature as the remainder of the ball and are then inserted in the recesses of the core G' . Thus the ball consists of five pieces—namely, the core G' , the two end pieces G^2 G^3 , and the two spots. Each of these pieces has been formed by compression in the cold state without the application of heat. Finally, the roughly-formed ball is compacted and baked by the application of heat and pressure in the usual manner.

I desire it to be understood that I make no claim in this application to the particular form of press and dies shown herein; but

What I do claim as my invention, and desire to secure by Letters Patent, is—

1. A mold comprising a tubular body open at both ends for the entrance of dies, and provided between its ends with transversely-movable plugs having ends adapted to extend into the bore of the tubular body and to engage a mass of plastic compressible material and retain the same therein.
2. A mold comprising a tubular body open at both ends and provided between its ends

with diametrically-opposed orifices perpendicular to the axis of said tubular body, and plugs movable transversely in said orifices and adapted to extend into the interior of said tubular body and to engage a mass of plastic compressible material placed therein and to retain the same in a fixed position.

3. As means for producing the central, or core-like portion of the composition ball, a tubular or female mold or die, provided with diametrically opposite, movable core-plugs, the ends of which may be set to protrude within bore of the hollow die, to produce in the molding operation cavities to receive number inserts, and capable of being withdrawn from within the bore of said die at pleasure; also a pair of male dies adapted to enter the opposite ends of the said female die, and to mold or compress into shape the central core-like portion of the ball, as hereinbefore specified; the whole arranged and operating so that after the molding of said central portion of the ball, the cores which produce the cavities for the inserts may be withdrawn from said cavities, and the molded ball portion then withdrawn from the mold, all substantially as and for the purposes hereinbefore set forth.

4. As means for molding a pool-ball, the combination, with a tubular or female die having radially-movable core-plugs, of two pairs of male dies, one pair of which is adapted to form, in conjunction with the core-plugs, the middle portion of the ball with cavities to receive inserts, and the other pair of which is adapted to form segmental body portions and compress them upon said middle portion, substantially as described.

ALONZO L. BURT.
